US00D967010S

(12) **United States Design Patent** (10) **Patent No.:** **US D967,010 S**
Liao (45) **Date of Patent:** **** Oct. 18, 2022**

(54) **BATTERY**

(71) Applicant: **Dongguan Lianguang Electronics Technology CO., LTD.**, Guangdong (CN)

(72) Inventor: **Zhibing Liao**, Henan Province (CN)

(73) Assignee: **Dongguan Lianguang Eletronics Technology Co., LTD.**, Dongguang (CN)

(**) Term: **15 Years**

(21) Appl. No.: **29/764,966**

(22) Filed: **Jan. 5, 2021**

(51) LOC (13) Cl. **13-02**

(52) U.S. Cl.

USPC **D13/103**

(58) **Field of Classification Search**

USPC D13/103, 107, 108, 110, 118, 119, 122, D13/184, 199
